OCTAVIAN G. I. O'HEIR, OF LOWELL, MASSACHUSETTS

SPRING DOOR AND WINDOW CHECK

Application filed December 12, 1930. Serial No. 501,905.

This device is a check or buffer for windows and doors. For doors, its purpose is to prevent slamming by receiving a door on a bow spring and for a window, it is intended to project slightly so as to prevent rattling.

When used on a door it will not only prevent banging or slamming, but at the same time will prevent rattling.

It can be made in different sizes for different sizes of doors or windows and, particularly for doors, can be provided with an additional or auxiliary resilient check in the form of a rubber buffer or additional spring.

It is small, efficient and very cheap to make.

In the drawing, Fig. 1 is a horizontal sectional view showing the device attached to a door frame with the door about to be closed.

Fig. 2 is an elevation of the device attached to a door frame as viewed from the left of Fig. 1.

Fig. 3 is a vertical sectional view considerably enlarged as on the line 3-3 in Fig. 1 viewed from the direction of the arrow, the device being set back, however, from the position shown in Figs. 1 and 2 and applied to a window instead of a door.

Fig. 4 is an elevation partly in section showing a modified type of the device applied to a door frame.

Fig. 5 is a view similar to Fig. 4 showing a modified type of the device applied to a window casing.

Fig. 6 is a view similar to Fig. 4 showing still another modification.

Fig. 7 is a perspective view of the type of device shown in Fig. 2.

Fig. 8 is a sectional view similar to Fig. 6 of a modification of the device before it is put in position.

Fig. 9 is a view similar to Fig. 8 of another modification.

In the drawing, A represents a door and B a frame the face 1 of the door A ordinarily striking the face 2 of frame B.

3 is the other face of frame B at right angles with 2.

C is the casing of my device formed with a tail 10 having screw holes 11 for screws

D by which it is fastened to the face 3 of frame B.

6 is the back, 7, 17 sides and 8 and 9 the ends which are bent over at 12, 12 to form the front and to act as guides and holders 55 for the bow spring F.

This spring F is bowed outwardly at 20 and thence bends at 21, 22 under the ends 13, 13 of the holders 12, 12 and thence curves around at 23 and 24 from where it is bent 60 back in reverse at the tips 25 and 26.

There should be plenty of room between the curves 23 and 24 and the inside of the ends 8 and 9 to permit free play and the bends at 21, 22 and tips 25 and 26 should be 65 so formed that bends 21, 22 normally engage the inside of ends 13, 13 and tips 25 and 26 should engage the back 6.

This spring F preferably also is so made that its bends, curves and tips and the elasticity of the spring are such that it can be slipped in between the ends 13, 13 or removed in the same way.

As shown in Fig. 4, the tail 10 may be 75 omitted and a casing H may be used. Casing H has sides 30 and 31, back 32, ends 33 and 34 which are bent over at the front as holders 35, 36 with ends 37 and 38 and is of substantially the same construction as casing 80 C except that the tail is omitted.

This may be inserted in the wall at 2 in recess 4 or where it is to be used on a window W, it may be inserted in a recess 39 in the runway R, being held in position by a screw 85 S. As shown in Fig. 3, the type with a tail 10 can be used to prevent rattling of a window such as W and the outer sides of the holders 12, 12 need not be flush with the edge 52 of the runway R.

This tailed form of my device can be very easily adjusted so that its spring will project more or less as required by the conditions.

While I prefer the above described form of spring, I can as shown in Fig. 6, use a 95 spring L bowed at 40, thence bent at 41 and 42 under the holders 35, 36 in a way similar to 21 and 22 but from there at 43 and 44 bent around in the reverse direction. These bends 43 and 44 should not extend out to the 100

ends of the casing H, but normally should engage holders 35, 36.

In Figs. 8 and 9, I show a casing M which is substantially the same as H, except that 5 the front parts forming the holders 50 and 51 are closer to the back 59 than where a different type of spring is to be used.

This spring 55 is bowed so as to curve under and preferably close to the ends 53 and 10 54 of holders 50 and 51 thence extends out at 56 and 57 so as to ordinarily rest against the back 59. This construction prevents rattling and the spring is of such length that it can spread when yielding.

15 In addition, however, in some cases I prefer to use a rubber or cork buffer 58 which as shown has a hollow back but which obviously might be solid.

This elastic check helps to take up the 20 shock as in case of a heavy door.

In Fig. 9, I show in place of the rubber buffer 58, a compound spring 68 shown as being flat at the back 60 where it rests 25 against the back 59 of casing M and rounded at 61 to fit the bow of 55 and having a double or S shaped middle portion 63.

The purpose of this is the same as that of the rubber buffer 58.

30 It is obvious that I might use as an auxiliary resilient check, a piece of rubber, a spring such as shown in Fig. 9, a spiral spring or any other kind of spring in connection with any of the other types of bow springs shown and described or these might 35 be omitted from the type of spring shown in Figs. 8 and 9.

For cheapness and to still further make my device resilient, I prefer to use a substantially one piece sheet metal construction 40 such as shown in Fig. 7.

The tail 10 is bent back upon itself at 100 to form the back side 17 while the front side 7 and the ends 8 and 9 including the bent 45 over front holders 12, 12 between which is the front spring opening, are all made of the same piece of metal without solder.

By making the holders 12, 12 of the form shown and springing at right angles from the back 6 and thence extending at another 50 right angle parallel with the back, these holders even if not made of springy sheet metal have some elasticity or yielding. This permits their ends to engage the part of the bow spring between the back and the ends, thus adding to the resiliency and avoiding rattling.

In every case, it is desirable that the spring should be so made with reference to the front 55 spring opening and the front holders and the casing itself, that a spring can be slipped in and out either with or without an auxiliary check such as 58 without destroying or distorting the holder.

I claim:

1. In a buffer for doors, the combination of a sheet metal casing formed of one piece of metal including attaching means, sides and a back from which integral top and bottom ends extend at right angles and are then bent and extend as holders short distances parallel with the back, whereby a spring opening is left in the front; with a bow spring positioned inside the casing and formed of a strip of spring sheet metal so bent out medially as to project through the spring opening in the front and to then extend under the holders and to then be doubled back so that the ends of the spring engage the back of the casing while the junctions between its bowed parts and its ends engage the tips of the front holders; and an auxiliary resilient check member between the spring and casing. 70

2. In a buffer for doors, the combination of a sheet metal casing formed of one piece of metal including an attaching tail, sides, and a back from which integral top and bottom ends extend at right angles and are then bent and extend as holders short distances parallel with the back, whereby a spring opening is left in the front; with a bow spring positioned inside the casing and formed of a strip of spring sheet metal so bent out medially as to project through the spring opening in the front and to then extend under the holders and thence back so that the ends of the spring engage the back of the casing while the junctions between its bowed part and its ends engage the tips of the front holders. 75

3. In a buffer for doors, the combination of a sheet metal casing formed of one piece of metal including an attaching tail, sides, and a back from which integral top and bottom ends extend at right angles and are then bent and extend as holders short distances parallel with the back, whereby a spring opening is left in the front; with a bow spring positioned inside the casing and formed of a strip of spring sheet metal so bent out medially as to project through the spring opening in the front and to then extend under the holders and to then be doubled back. 80

4. In a buffer for doors, the combination of a casing including sides, a back, top and bottom ends and holders parallel with the back, whereby a spring opening is left in the front; with a bow spring positioned inside the casing and formed of a strip of spring sheet metal so bent out medially as to project through the spring opening in the front and to then extend under the holders and to then be doubled back. 85

OCTAVIAN G. I. O'HEIR.
